RACKET STRINGING MACHINE

John E. Darby, New Orleans, La.

Application August 20, 1935, Serial No. 37,065

4 Claims. (Cl. 273—73)

The present invention relates to new and useful improvements in machines for restringing tennis rackets and has for one of its important objects to provide, in a manner as hereinafter set forth, an apparatus of this character embodying a novel construction and arrangement through the medium of which the original shape of the racket will be retained.

Another very important object of the invention is to provide a machine of the aforementioned character through the medium of which the strings may be expeditiously and uniformly tightened to the desired tension without damaging said strings.

Still another important object of the invention is to provide a tennis racket re-stringing machine embodying a construction which is such that after the tightening or tensioning operation has been performed, it will leave both hands of the operator free to do any work desired.

A still further important object of the invention is to provide a tennis racket re-stringing machine embodying novel means for controlling or regulating the tension to which the strings are subjected.

Other objects of the invention are to provide a tennis racket re-stringing machine of the character described which will be comparatively simple in construction, strong, durable, highly efficient and reliable in use, compact, light in weight and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a machine constructed in accordance with the present invention.

Figure 2 is a view partially in vertical section and partially in side elevation of the invention.

Figure 3 is a vertical sectional view through the tightening or tensioning mechanism.

Figure 4 is a view in vertical transverse section, taken substantially on the line 4—4 of Figure 3.

Figure 5 is a horizontal sectional view, taken substantially on the line 5—5 of Figure 3.

Figure 6 is a vertical longitudinal sectional view, taken substantially on the line 6—6 of Figure 4.

Figure 7 is a vertical sectional view through

the adjusting mechanism, taken substantially on the line 7—7 of Figure 3.

Figure 8 is a detail view in horizontal section through the string gripping unit or device.

Figure 9 is a detail view in bottom plan of the string gripping unit or device.

Figure 10 is a detail view in horizontal section, taken substantially on the line 10—10 of Figure 3.

Figure 11 is a horizontal sectional view, taken substantially on the line 11—11 of Figure 3.

Figure 12 is a detail view in vertical section, showing the means for connecting the tensioning mechanism to the foot pedal for actuation thereby.

Figure 13 is a detail view in front elevation of the dial.

Referring now to the drawings in detail, it will be seen that the embodiment of the invention which has been illustrated comprises a base 1 from which a tubular standard 2 rises. Fixed on an upper portion of the standard 2 is an arm 3. The reference numeral 4 designates generally a clamp which is rotatably mounted on the upper end portion of the standard 2 above the arm 3.

As illustrated to advantage in Figures 1 and 2 of the drawings, the clamp 4 includes a frame 5 having a hub portion 6 journaled on the standard 2 and resting on the inner end of the arm 3. Pivotedly mounted, at an intermediate point, on the frame 5 are vertically arranged jaws 7 which are adapted for engagement with the racket 8 in a manner to firmly secure said racket in position. Extending rotatably and slidably through the lower end portions of the jaws 7 are actuating screws 9 which are threaded into the frame 5. Coil springs 10 are provided on the screws 9 and engaged with the jaws 7 for yieldingly urging said jaws toward inoperative position. At its lower end, the hub 6 of the frame 5 is provided with a horizontal flange 11 having sockets 12 in its lower face. The purpose of the sockets 12 will be presently set forth.

The reference numeral 13 designates a latch for the clamp 4 in the form of a vertical rod which extends slidably through the inner end portion on the arm 3 for engagement selectively in the sockets 12. The lower end portion of the latch 13 is slidable in a guide 14 on the standard 2. Pivotedly connected to the lower end of the latch 13 is a foot pedal 15 the inner end of which is adapted to rest on a stop 16 on the standard 2. Projecting from the base 1 is an extension 17 from which a post 18 rises, said post passing through the foot pedal 15 and functioning as a guide therefor.

Mounted vertically on the outer end of the arm 3 is a substantially tubular housing 19. At its upper end, the housing 19 is enlarged, as at 20, said enlargement extending toward the clamp 4. 5 Journalized in the enlarged upper portion 20 of the housing 19 is a toothed pulley 21. Slidably mounted on the upper end of the housing 19 is a gripper which is designated generally by the reference numeral 22. The gripper 22 comprises a 10 plate 23 having a longitudinal channel 24 therein, said plate resting slidably on out-turned flanges 25 on the upper end of the housing 19. Spaced guides 26 are secured on opposite sides of the plate 23, and engaged under the flanges 25 15 for slidably securing said plate in position, said guides 26 projecting over the channel 24.

Mounted for lateral and longitudinal sliding movement in the channel 24 are co-acting jaws 27 which are adapted to receive and grip the string therebetween. Referring now to Figure 8 20 of the drawings, it will be seen that the outer edges of the jaws 27 and the opposed vertical side walls of the channel 24 have formed therein cam pockets or notches 28 which receive rollers 29. Coil springs 30 are secured, at one end, to the plate 23 and at their other ends to the jaws 27 for causing said jaws to move together or toward each other substantially at the beginning of the tensioning operation.

30 The jaws 27 are retained against longitudinal movement relative to each other through the medium of a plate 31 (see Figure 9) which is fixed transversely on one of said jaws, said plate extending beneath the other of said jaws and having a slot 32 therein in which a pin 33 on said other jaw is slidably engaged. The plate 23 is recessed, as at 34, to slidably accommodate the plate 31.

40 Mounted on the lower side of the plate 23 is a rod 35 which passes slidably through an eye 36 formed on the upper portion of the housing 19. A coil spring 37 (see Figure 6) encircles the rod 35 and is engaged with the upturned inner end portion 35' thereof for yieldingly urging the gripper 22 toward retracted or inoperative position. 45 The upturned end portion 35' of the rod 35 is anchored in any suitable manner in the plate 23, as best seen in Figure 6 of the drawings. A stop screw 38 is threaded into the outer end of one of the jaws 27 for engagement with an upturned flange 39 (see Figure 3) on the upper end of the housing 19 for opening said Jaws 27 when the gripper is returned to inoperative position by the spring 37.

55 The housing 19 is open at its lower end for the reception of a vertically movable tube 40 which is slidable on the post 18, said tube 40 being operatively connected to the foot pedal 15 by links 41. At its upper end, the tube 40 terminates in 60 an internal flange 42. Slidably engaged in the upper end portion of the tube 40 and rising therefrom is a rack bar 43 having a head 44 on its lower end. A chain 45 is connected, at one end, to the upper end of the rack bar 43 and at its other end 65 to the inner end of the gripper 22, said chain being trained over the pulley 21. The chain 45 is operable in an opening 46 which is provided therefor in the upper portion 20 of the housing 19. A coil spring 47 is mounted on the rack bar 43 in 70 the tube 40 and has one end engaged with the head 44 and its other end engaged with the flange 42 for elevating said tube 40 and the foot pedal 15. The spring 47 also constitutes a resilient connection between the tube 40 and the rack bar 43.

75 Slidably mounted on the upper portion of the

tube 40 in the housing 19 and rising above said tube 40 is a sleeve 48 having mounted in its upper end portion a flange 49. The sleeve 48 is provided, at its lower end, with an extension 50 in which one end portion of a lock 51 is engaged. 5 The lock 51 is in the form of a plate (see Figures 3 and 11) which is slidable on the post 18 and which, when swung vertically or "cocked", is adapted to frictionally grip said post in a manner to arrest downward movement of the tensioning mechanism. The lock 51 is carried by the tube 40, said tube having formed therein diametrically opposite openings which are so formed as to permit sufficient vertical swinging movement of said lock for same to function.

10 Adjustably mounted on the upper portion of the rack bar 43 is a tubular member 52 which extends slidably into the upper portion of the sleeve 48 and terminates, at its lower end, in an external flange 53 for engagement with the flange 49. 20 Formed integrally with the upper portion of the tubular member 52 is a casing 54 which projects laterally through an opening or vertical slot 55 which is provided therefor in the housing 19. Rotatably and slidably mounted in the casing 54 25 is a shaft 56 (see Figure 5) having fixed on its outer end portion an operating wheel 57. Fixed on the inner end portion of the shaft 56 is a pinion gear 58 which is constantly in mesh with the rack bar 43. The gear 58 is engageable with a lug 30 59 in the casing 54 for positively securing the tubular member 52 in adjusted position relative to the rack bar 43. A coil spring 60 yieldingly urges the gear 58 toward the locking lug 59. A pointer 61 is mounted on an outer portion of the shaft 56 for co-action with a dial 62 on the outer end of the casing 54 to facilitate securing the desired adjustment.

35 Briefly, the operation of the device is as follows:—

40 The racket to be re-strung is secured in position on the clamp 4 and said clamp is rotated to bring the string to be tightened into alignment with the gripper 22. The string is inserted between the jaws 27 and the operator then presses 45 downwardly on the foot pedal 15. When this is done the latch 13 is elevated and engages in one of the sockets 12 for locking the clamp 4 against rotation. Downward pressure on the foot pedal 15 also moves the gripper 22 away from the racket 8 on the clamp 4 in a manner to tension the string. As the gripper 22 moves outwardly or 50 away from the racket 8 the spring 37 is compressed, the stop screw 38, which is mounted in one of the jaws 27, is moved out of engagement 55 with the flange 39 and the comparatively weak springs 30 are thus permitted to move said jaws 27 toward each other into engagement with the string. Then, the greater the tension that is exerted on the string the greater will be the gripping action of the jaws 27 by reason of the rollers 29 and the cam pockets 28. Before the tensioning operation begins the desired adjustment is made by moving the tubular member 52 upwardly or 60 downwardly on the rack bar 43 through the medium of the hand wheel 57. As the foot pedal 15 is swung downwardly the tube 40, of course, also moves downwardly on the post 18 and the rack bar 43 is likewise moved downwardly, the spring 47 being compressed between the head 44 65 and the flange 42. The sleeve 48 also moves downwardly with the tube 40 until the flange 49 engages the flange 53, thus retarding said sleeve 48 relative to the tube 40 and causing the lock 51 to grip the stationary post 18 in a manner to 70 75

prevent further downward movement of said tube 40. By pulling the shaft 56 outwardly against the tension of the spring 60 in a manner to disengage the gear 58 from the lug 59 the tubular member 52 may be raised or lowered on the rack bar 43, thus increasing or decreasing the distance between the flanges 49 and 53 for causing the lock 51 to function at any desired predetermined point. When the shaft 56 is released the spring 10 60 again engages the gear 58 with the lug 59 for locking the tubular member 52 and the rack bar 43 together. When the operation has been completed the several springs return the tensioning mechanism to retracted or inoperative position 15 and the latch 13 drops by gravity in inoperative position.

It is believed that the many advantages of a racket stringing machine constructed in accordance with the present invention will be 20 readily understood, and although a preferred embodiment of the device is as illustrated and described, it is to be understood that changes in the details of construction and in the combination and arrangement of parts may be resorted 25 to which will fall within the scope of the invention as claimed.

What is claimed is:—

1. A racket stringing machine comprising a supporting structure, a clamp for a racket rotatably mounted on said supporting structure, a string gripper operatively mounted on the supporting structure, and common means for actuating said gripper and for releasably locking the clamp against rotation.
2. A racket stringing machine comprising a supporting structure, a clamp for a racket ro-

tatably mounted on said supporting structure, a string gripper slidably mounted on the supporting structure, a lever, means operatively connecting the lever to the gripper for actuating said gripper, adjustable means for limiting the movement of the lever, and means operable by said lever for releasably securing the clamp against rotation on the supporting structure. 5

3. A racket stringing machine comprising a supporting structure, means for mounting a racket on said supporting structure, a gripper operatively mounted on the supporting structure and adapted to tension the strings of a racket, a manually operable lever mounted on the supporting structure, a yieldable connecting 15 means operatively connecting the gripper to the lever, and adjustable means for arresting said connecting means after a predetermined movement of the gripper.

4. A racket stringing machine comprising a standard, a clamp for a racket rotatably mounted on said standard, an arm mounted on the standard, a gripper slidably mounted on the arm and engageable with a string from the racket for tensioning said string, a post mounted on the 20 supporting structure, a lever, a latch connected to said lever and engageable with the clamp for releasably securing said clamp against rotation, a tube slidable on the post and connected to the lever for actuation thereby, a resilient connection coupling the gripper to the tube for actuation thereby, and adjustable means for locking the tube to the post against actuation by the lever after predetermined movement of said tube 25 in one direction. 30 35

JOHN E. DARBY.
